MACHINE FOR APPLYING AND CUTTING
ADHESIVE TAPE

Hubert J. Vachon, Lynn, Mass., assignor to Boston Machine Works Company, Lynn, Mass., a corporation of Massachusetts

Application November 18, 1957, Serial No. 697,017

1 Claim. (Cl. 12—59.5)

This invention relates to a machine for pulling adhesive tape from a roll of such tape, applying the tape to the back seam of a shoe upper, or equivalent work piece, and automatically cutting the tape so that the cut end of the portion applied to the back seam of an upper will be spaced a predetermined distance from the trailing end of the same. The machine performs substantially the same function as that described and illustrated in my U. S. Patent No. 2,755,492, granted July 24, 1956, but with a construction that is simpler and more reliable, particularly when operated rapidly.

For a more complete understanding of the invention, reference may be had to the following description thereof, and to the drawings, of which—

Figure 1 is a side elevation of a machine embodying the invention;

Figure 2 is a perspective view, on a larger scale of a part of the mechanism shown in Figure 1;

Figure 3 is a section on the line 3—3 of Figure 2;

Figure 4 is a section on the line 4—4 of Figure 3;

Figure 5 is a fragmentary front elevation of the switch operating mechanism viewed as indicated by the line 5—5 of Figure 1;

Figure 6 is a fragmentary perspective view of a shoe upper after a strip of tape has been applied to the back seam;

Figure 7 is an elevation of a portion of the mechanism shown in Figure 1, with a work piece being introduced thereto;

Figure 8 is a similar elevation showing the work piece about to complete its course through the machine;

Figure 9 is a fragmentary section on the line 9—9 of Figure 7;

Figure 10 is a fragmentary section on the line 10—10 of Figure 8;

Figure 11 is a fragmentary section on the line 11—11 of Figure 8; and

Figure 12 is a fragmentary section, on a larger scale, on the line 12—12 of Figure 7.

The machine as shown in Figure 1 includes a main frame 30 on which is carried a pair of feed rolls 32 and 34. The upper feed roll 32 is provided with teeth 36 extending around its circumference to grip the work as it is passing between the feed rolls. The lower roll 34 is provided with a circumferential groove 38 (Figure 9) to receive the back seam 40 of a shoe upper 42 and to press against this seam a strip of tape 44 which is coated with an adhesive on one face thereof. If the work pieces are other than seamed shoe uppers, the peripheries of the feed rolls are shaped accordingly.

The feed roll 32 is mounted on a shaft 46 which is journaled in the main frame 30 and is constantly driven by any suitable means (not shown). The roll 34 is an idle roll journaled in the upper end of an upright 48 which is rockably mounted at its lower end on a block 50. Rockable with the upright 48 is a lever 52 the upper end of which is attached by a link 54 to the short arm

2

of a bell-crank 56. The long arm of the crank projects upward (Figure 1) and is manually operated to swing the upright 48 toward the right so as to move the feed roll 34 clear of the feed roll 32 when it is desired to operate on the back seam of the shoe upper. In most cases the shoe upper is in the form of a closed loop which must be placed over the upright 48 so that when the back seam has passed through between the feed rolls 32 and 34, the upper will then be free.

10 The adhesive tape 44 is drawn from a roll 58 carried by a suitable bracket 60 which extends upward on the main frame 30. The tape leads through an upper detent 62 which is mounted at the end of a rocking lever 64 past a guide 66 on the main frame and a guide 68 on a vertical slide bar 70 to a lower detent 72 carried at the lower end of the bar 70. A tension spring 71 attached to the rock lever 64 tends to pull the slide bar 70 downward between a fixed guide element 73 on one side of the slide bar and an adjustable lug 81 on the other side, the guide element and the lug being mounted on the main frame 30. The detent 72 is preferably a light leaf spring bearing against a knurled guide roll 74 mounted at the lower end of a bar 70. The rocking lever 64 is pivoted as at 76 to the main frame so that when the lever 64 is rocked, the bar 70 is raised and lowered together with the guide 68 and guide roll 74 mounted thereon. The normal position of the bar 70 is shown in Figure 1, the knurled roll 74 being adjacent to the nip of the feed rolls 32 and 34 and just below the level of a fixed knife 80 which is mounted on the main frame.

When a work piece has been fed through between the feed rolls 32 and 34, the bar 70 is raised by the rocking lever 64 to lift the knurled roll 74 above the level of the knife 80 (Figure 8). The lug 81 bears against an edge of the slide bar 70 and keeps the knurled roll 74 in front of and spaced from the knife 80 when the slide bar is in its lowered position as shown in Figures 1 and 7. When the slide bar 70 is raised by energization of a solenoid 75, the armature 77 of which is attached to the rock lever 64, the lug 81 can enter a recess 83 in the edge of the slide bar 70, permitting the slide bar to swing to the left by the tension on the tape 44, as indicated in Figure 8, thus bringing the portion of the tape between the knurled roll 74 and the nip of the feed rolls 32 and 34 strongly against the edge of the knife 80 which is preferably serrated as indicated in Figure 12 so that the tape is thus severed. Whenever the rocking lever 64 is rocked to raise the bar 70, the upper end of the lever on which the upper detent 62 is mounted 45 swings downward thus pulling some slack tape 44 loose from the roll 58. When the lever 64 rocks back to the position shown in Figure 1 this slack hangs in a loop and can be drawn through the detents 62 and 72 with very little resistance.

50 A suitable guide 82 for the work piece is mounted on the upright 48. This guide is curved as indicated in Figure 1 so that its upper end is close to the periphery of the feed roll 34 and is triangular in cross-section (Figure 9). Cooperating with the guide 82 are guides 84 and 85 which are mounted on a vertical rod 88. This rod slides through bearings in a bracket 90 which is secured to or is a part of the main frame. The guides 84 and 85 are adapted to engage the sides of the back seam 40 on a shoe upper so as to keep the seam aligned with the tape passing over the roll 74. These guides are resilient and are adjustably spaced apart by a thumb screw 92.

55 The bracket 90 includes two bearing blocks 94 and 96 through which the rod 88 and another rod 98 slidably extend. A fork 100 on the rod 88 straddles a fixed pin 102 on the block 94 to keep the guides 84 and 85 properly oriented. A spring 104 is compressed between the

block 96 and a collar 106 on the rod 88 to hold the guides 84 and 85 yieldingly down.

Between the guides 84 and 85 is the nose 108 on an arm of a U-shaped trigger 110 which is adjustably secured by its other arm 112 to the lower end of the rod 98. The lower end is slotted and screw-threaded to receive said other arm which is clamped in the slot by a knurled nut 114. When the nut 114 is loosened, the trigger can be adjusted toward or from the nip of the feed rolls 32 and 34.

Near the upper end of the rod 98 is fixed a member 116 carrying a finger 118 which is adapted to engage and press the button 120 of a micro-switch 122. The latter is in series with the solenoid 75 so that when the switch 122 is closed, the solenoid is energized; and when the switch is open, the solenoid is deenergized. The member 116 has a lateral forked projection 124 straddling a pin 126 fixed in the bracket 90 to keep the trigger 110 properly oriented. The rod 98 and the parts carried thereby are pressed downward by a spring 130 which encircles the rod between the block 94 and a collar 132 fixed on the rod.

The operation of the mechanism is as follows: When the back seam of a shoe upper is advanced on the guide 82 between the guides 84 and 85, it pushes the nose 108 of the trigger upward, thus raising the finger 118 from the switch 122 and causing the switch to open. This deenergizes the solenoid 75 so that the slide bar 70 and the guide rolls 74 carried thereby take the position illustrated in Figures 1 and 7 and remain in such position while the back seam is advancing between the guide 82 and the nose 108. When the back seam moves beyond the nose 108, the latter is no longer supported thereby and drops to the position shown in Figure 8. This results in the closing of the switch 122 and the energization of the solenoid 72. The lever 64 is rocked to raise the slide bar 70 and guide roll 74 to the position shown in Figure 8, exposing the tape to contact with the knife 80. As the leading portion of the tape is being pulled by the feed rolls 32 and 34, it is drawn strongly against the knife 80 and is severed thereby. Ordinarily it is desirable that the severed end of the cut-off piece of tape be spaced from the adjacent end of the back seam 40, as indicated in Figure 6. The extent of this spacing will depend on how far the end of the seam 40 is from the nip of the feed rolls when the

tape is cut. Hence the extent of the spacing can be determined by adjusting the trigger 110 toward or from the nip of the feed rolls. By adjusting the trigger 110 a sufficient distance toward the nip, the severed end of the cut-off piece of tape can be made to be flush with the edge of the shoe upper.

For reliable feeding action by the rolls 32 and 34, the idle roll 34 may be made, as indicated in Figures 9, 10 and 11, with a central grooved ring 134 of steel to back up the seam on which the tape 44 is being pressed. This central ring is flanked by two rubber rings 136 and 138 which provide frictional traction for the portions of the upper adjacent to the seam.

I claim:

In a tape applying machine, a frame, a driven feed roll supported by said frame for constant rotation about a fixed axis, an idle feed roll, support means for said idle roll operable to move said idle roll to and from tangential engagement with said driven roll, a guide member for work pieces mounted on said support means adjacent to the periphery of said idle roll, a trigger mounted adjacent to said guide member and movable from said guide member by the insertion of a work piece between said trigger and said guide member, an electric switch operable by movement of said trigger, a solenoid controlled by said switch, an armature in said solenoid, a rock lever mounted on said frame, means operatively connecting said rock lever to said armature to be rocked by energization of said solenoid, a slide bar attached to and operable by said rock lever, means on said frame for supporting a roll of tape and guiding the tape to the nip of said feed rolls, said guiding means including a roll mounted on said slide adjacent to the nip of said feed rolls and adapted to be raised by said slide when the solenoid is energized, said trigger being adjustable toward and from said nip of the feed rolls and adapted to ride on a work-piece moving on said guide member, and means on said frame operating when said guide roll is raised to sever the tape near the nip of said feed rolls.
